UNITED STATES PATENT OFFICE

2,306,404

SPACE DISCHARGE RELAY

Louis M. Potts, Evanston, Ill., assignor to Tele-type Corporation, Chicago, Ill., a corporation of Delaware

Application February 26, 1940, Serial No. 320,846

19 Claims.

(Cl. 178—70)

This invention pertains to telegraph systems and particularly to such systems in which space discharge devices are embodied as parts thereof with functions of transmitters, receivers or relays.

The invention further pertains particularly to systems in which space discharge devices respond to a comparatively short controlling impulse of signaling current and then function to deliver lengthened impulses to operate the apparatus in a controlled circuit of a telegraph system.

An object of the invention is to provide space discharge apparatus in telegraph systems where transmission is effected rapidly by electrical impulses, each of short duration, to effect a fully reliable operation in the signal responsive mechanical elements of the apparatus.

A further object of this invention is to limit the period during which the space discharge devices operate to the time necessary to operate the apparatus in a controlled circuit.

A feature of the invention is the provision of a system of signal repeating devices in which one device is used to receive a signal and another device is used to retransmit the signal, the retransmitting device being designed to give a retransmitted signal of full time value in response to a received signal impulse of shorter time value.

In one form of the invention, each received signal is continued in the repeating circuit or in the work circuit until a signal of a contrasting characteristic is received.

In another form of the invention, the received signal impulse is repeated into a work circuit by a trigger member and is maintained by a residual condition while the unit of work is being effected, a mechanical operating member of the receiving unit then effecting resetting of the trigger member of the receiving device to terminate the work signal current impulse.

A more complete understanding of the invention may be had from the following description taken in conjunction with the accompanying drawing, in which

Fig. 1 illustrates a system embodying the invention; and

Fig. 2 illustrates another structure embodying the invention.

Fig. 1 illustrates a relay system in which trigger tubes are responsive to short received signal impulses and in which the plate circuits of the trigger tubes are opened by mechanical switch contacts or relay contacts to terminate the currents in the plate circuits. In this exemplification of the invention, the work to be done is to effect the operation of relay armatures in an electromag-

netic relay and upon the operation of one of such armatures the plate circuit of the controlling trigger tube is terminated by contacts controlled by the armature.

5 Fig. 2 illustrates a mechanical system in which trigger tubes are responsive to short received signal impulses and in which electromagnets of trigger nature are operated in turn by the trigger tubes to terminate the currents in the plate circuits of the trigger tubes. In this modified exemplification, the work to be done is to effect the operation of a relay armature. Upon the operation of such an armature the plate circuit of the trigger tube is opened and concomitantly a

15 circuit is closed to effect a further unit of work.

Referring now more particularly to Fig. 1 there is disclosed a telegraph system, preferably a synchronous multiplex system, comprising a transmission timing contact 2, a synchronous transmitting distributor 18, a pair of space discharge devices 5 and 6 controlled by the distributor and an apparatus 9 in turn controlled by said space discharge devices. A constantly rotating cam 1 carried on a shaft 21, operates contact 2 periodically to complete a transmission circuit, to be presently defined, from transmitting distributor 18 to either of the gas filled tubes 5 or 6. Neutral relays 7 and 8 through their armatures condition a circuit to control apparatus 9 in response to signal combinations transmitted from distributor 18. In this figure, 9 is illustrated as a polar relay controlling retransmission into a conductor 10, but it may well form part of any signal controlled apparatus.

35 The transmitting distributor 18 includes ten segments, A—1 to A—5 for channel A and B—1 to B—5 for channel B. Associated with segments B—1 to B—5 is a tape controlled permutation transmitter 19 which comprises transmitting members 3 and 4 engageable by a plurality of tongues 26 to place marking or spacing condition on these segments in response to a perforated tape controlling transmission from transmitter 19. Likewise a tape controlled transmitter 28 40 conditions segments A—1 to A—5 in response to signal combinations in a perforated tape. A double brush 16 is carried by shaft 17 of transmitting distributor 18 and bridges ring 25 and the segments of the distributor successively to transmit code signal combinations. Cam 1 is rotated by shaft 21 through a 10 to 1 gearing from shaft 17 and operates its follower 22 to close contact 2 for a short period in each revolution of cam 1 to complete a transmission circuit as follows: 45 ground, battery 23, resistor 24, contact 2, ring 25, 50

brushes 16, the distributor segment with which brush 16 has its instant engagement, tongue 28 in transmitter 19 or 23 connected to the particular distributor segment, line conductor 27 and 28 depending on the positionment of the particular tongue 28 and grid of tube 5 or 6.

Plate circuit 38 of tube 5 includes battery 31, winding of relay 7, contacts 32, 33 of relay 7, plate 35, cathode 36, conductor 37 and potentiometer 38 to battery 31. A holding circuit for relay 7 when operated, and when relay 8 is de-energized, includes battery 31, winding of relay 7, contact 32 and tongue 11, of relay 7, tongue 39 and contact 40 of relay 8 and to ground.

Plate circuit 41 of tube 6 includes battery 31, resistor 42, winding of relay 8, plate 43, cathode 44, conductor 45 and potentiometer 38 to battery 31. Relay 7 has a further contact 46 connected to ground, and relay 8 has a further contact 47 connected to resistor 42.

Tongue 14 of relay 7 is provided with a pair of retransmitting contacts comprising a marking contact 51 connected to negative battery 52, and a spacing contact 53 connected to positive battery 54. Tongue 14 is connected to line conductor 55 and over that conductor it is connected to a polar signal responsive device 9.

Operation of the structure illustrated in Fig. 1 is as follows: The structure is shown in normal condition which is represented as continuous transmission of a signal of marking nature over conductor 55, initiated by a marking impulse from segment B—5, the conductors 27 and 28 being instantly without potential because contact 2 is open. Plate circuit 38 of tube 5 is open at contact 33 of energized relay 7 which is held energized by its described holding circuit.

Upon momentary closure of the transmitting contacts 2 for a spacing impulse, positive battery 23 will be connected through segment A—1, brush 16 and a tape-controlled contact 26 and line conductor 28 to grid of tube 6, rendering tube 6 conductive, permitting current in plate circuit 41 of tube 6, energizing relay 8 and thus interrupting the holding circuit of relay 7 at contact 40, which releases its tongue 11 to be operated by a retractile spring (not shown) into engagement with contact 46, thus shunting the winding of relay 8 and the plate circuit through tube 6 through the following circuit: ground, battery 31, resistor 42, contact 47, armature 38 of relay 8, armature 11 of relay 7, contact 46, and ground. Both relays 7 and 8 thus are de-energized, and all current is shunted from the plate circuit in tube 6, terminating the conductive condition of that tube.

Subsequently, upon momentary closure of the transmitting contacts 2 for a marking impulse, positive battery 23 will be connected through brush 16 and a tape controlled contact 26 and line conductor 27 to grid of tube 5, rendering tube 5 conductive, permitting current through winding of relay 7, which forms its holding circuit and operates its contacts into the conditions shown in the drawing, thus opening the plate circuit 38 of tube 5.

By energization and de-energization of relay 7, tongue 14 has been operated between the two contacts 51 and 53 alternately, effecting in line conductor 55 and in signal responsive device 9 a series of signals corresponding to signals generated by contacts 2 in co-operation with brush 16 and tape controlled transmitters 19 and 23.

The mechanical work to be done by relay 7, in response to control by plate current of tube 75

5, is the movement of tongue 11 to engage contact 32, after which current in the described holding circuit effects all subsequent functions. Upon completion of the work of engaging contact 32, the tongue 11 disengages contact 32 from contact 33, stopping all plate current in tube 5. The mechanical work to be done by relay 8 in response to control by tube 6 is the movement of tongue 39 to engage contact 47 and to release tongue 11 for movement into engagement with contact 46. Upon completion of the work, the described shunt through circuit elements 47, 38, 11 and 46 stops all plate current in tube 6. The tubes 5 and 6 are rendered conductive for only a very short interval of time because in accomplishing their functions, that is, the energization of relay 7 or 8, they are rendered non-conductive. However, although the tubes are operative for only a short period, the signal controlled apparatus 9 is conditioned by elongated signal impulses since the repeating tongue 14 is positioned to repeat elongated signals by the operation of one of the tubes 5 or 6 in response to received signal impulses and the positionment of tongue 14 is maintained until a signal impulse is transmitted from distributor 18 which reverses the setting of tongue 14.

An alternative structure embodying the invention is illustrated in Fig. 2.

The invention again has been illustrated in connection with a synchronous multiplex telegraph system and more particularly to the receiving terminus of such a system. A receiving distributor 103 includes a plurality of very short segments 104, of which segments C—1 to C—5 form a portion of channel C and segments D—1 to D—5 form a portion of a channel D. A distributor brush 120 carried by distributor shaft 121 distributes signal impulses received over the multiplex transmission line 122 to the segments 104.

At the receiving end of the multiplex system there are provided a plurality of space discharge devices 111 adapted to be controlled by signals received over line 122. The space discharge devices 111 are gas filled trigger tubes which are normally non-conductive but which may be rendered conductive by a control grid 123. Each of the control grids 123 is directly connected to a segment 104 of the synchronous receiving distributor and when a marking impulse is received from the transmission line 122, it is directed to the grid of the tube associated with the distributor segment contacted by brush 120 during the particular signal impulse period and renders that tube conductive. When a spacing signal is received, the tube connected to the distributor segment instantly contacted by brush 120 is not rendered conductive since a spacing signal is either a no-current interval or an impulse of reversed polarity to that of a marking signal.

Also located in this receiving end of the transmission line there is a plurality of double wound magnets 105, equal in number to the plurality of space discharge devices 111. Each double wound magnet 105 has a biasing winding 109 continuously energized over a simple circuit including ground, winding 109 and grounded positive battery (only two such circuits have been indicated in Fig. 2). The second, or neutralizing, winding 114 of each magnet 105 is included in the plate circuit of one of the space discharge devices 111, as will presently appear.

There is an armature 108, in the form of one

arm of a pivoted bell crank, associated with each magnet 105 to be controlled thereby. Assisted armature action is afforded by the engagement of a cam 106 carried directly by shaft 121, or driven synchronously therefrom, with the other arm 107 of the bell crank. Cam 106 is so oriented on its shaft that it will return armatures 108 to the poles of their respective magnets 105 just prior to the time at which the distributor brush 120 contacts the distributor segments connected to the space discharge devices which control the magnets through their plate circuits. Each magnet through its biasing winding 109 retains its armature in its attracted position until its controlling winding is energized through the reception at the gas tube 111 associated with the particular magnet of a marking impulse which renders the tube conductive and energizes the neutralizing winding through a circuit 113 including the plate of the particular tube 111, contact pair 112, neutralizing winding 114, battery, and the filament of the tube. In response to the energization of the neutralizing winding 114 a spring connected to the armature is effective to withdraw the armature from its magnet.

Each armature 108 controls two contact pairs, pair 112 in the above defined plate circuit and pair 116 which closes a circuit 117. Since a two-channel multiplex system employing a five unit code has been illustrated, there are ten segments in distributor 103, ten space discharge devices 111, ten magnets 105 controlled thereby and ten circuits 117 conditioned by the magnets. Five of the circuits 117 form a continuation of channel C, and the remaining five form a continuation of channel D. These channels C and D may lead to a printer, a regenerative repeater, or any signal controlled apparatus.

Cam 120 carried by synchronized shaft 121 operates cam-controlled switches 131 and 132 to generate sixth-impulse signals on conductors 133 and 134. Line 133 is associated with one channel, as channel C, and line 134 is associated with the other channel and the sixth impulse supplied over these conductors operates the apparatus conditioned by the signal impulses transmitted over circuits 117 thereto in well known multiplex operation.

The operation of the structure illustrated in Fig. 2 is as follows: The structure is shown in condition of transmission of a series of signals of spacing nature. Upon receipt of a marking signal impulse from line 122 distributed through one distributor segment 104 to grid 123 of the tube connected thereto, the tube 111 becomes conductive and current flows in its plate circuit 113 through winding 114 of the magnet 105 associated with the particular tube 111 neutralizing the magnetic field of that magnet set up by current through its winding 109 and releasing the armature 108.

By its motion in release, the armature 108 opens the plate circuit 113 and closes the controlled circuit 117 thereby rendering the tube 111 non-conductive and repeating the received signal impulse. Subsequently, cam lobe 106 engages lever 107 and moves armature 108 to its magnet 105 now re-energized by current in winding 109. Since the distributor segments 104 are very short the circuits to the control grids of tubes 111 are conditioned for a very short period of time but this period is sufficient to cause tube 111 to become conductive also for a short period of time to release the armature 108 of a magnet 75

105 when a marking impulse is received. However, the marking signal repeated into the circuit 117 controlled by the particular tube rendered conductive upon the reception of a marking impulse will be materially lengthened affording greater operating time for the apparatus connected to circuits 117 because the armature 108 is not restored to its magnet 105 opening circuit 117 until cam 106 engages the arm 107 which engagement will not occur until shaft 121 has completed nearly a full revolution.

The telegraph system employed on circuits 117 is one in which marking signals are intervals of current and spacing signals are intervals of no-current. When a spacing signal is received over line 122, the tube associated with the distributor segment conditioned by this signal is not rendered conductive, and accordingly, the magnet controlled by this tube retains its armature and holds contacts 116 of circuit 117 open and repeats a lengthened spacing signal.

The mechanical work to be done by plate current of tube 111 acting through magnet 105 is the movement of the armature 108 and contacts 112 effected by the neutralization of the normal magnetic field of magnet 105. Upon completion of this work, contacts 112 are disengaged from each other which stops the operating plate current.

30 While the invention has been described in connection with specific illustrative systems, these are capable of modification without departing from the spirit or scope of the invention, which is determined only by the scope of the appended claims.

What is claimed is:

1. In a telegraph relay set, a gas filled tube having a grid under the control of received signal impulses, an electromagnetic relay having a winding included in the plate circuit of said tube, an armature for said relay, normally closed contacts in said plate circuit mechanically actuated by said armature in response to the energization of said relay winding and responsively effective to open said plate circuit, and signal repeating means operated in accordance with the effectiveness of said tube under the control of said armature to repeat signals received by said tube.

40 2. In a telegraph system, a gas filled tube responsive to a received electrical signal impulse, an electromagnetic winding and normally closed contacts included in the plate circuit of said tube, a mechanical member operable by said winding to engage and open said contacts in said plate circuit in response to the energization of said winding, and signal repeating means operated in accordance with the effectiveness of said tube under the control of said mechanical member to repeat signals received by said tube.

50 3. In a telegraph system, a signal impulse generator, a gas filled tube responsive to electrical signal impulses emitted by said generator, an electromagnetic winding included in the plate circuit of said tube, a mechanical member operable in response to the electrification of said winding, a holding circuit for said winding closed by said member in its operated position, means operable by said member to close said holding circuit and to interrupt current in said plate circuit, and signal repeating means operated in accordance with the effectiveness of said tube under the control of said mechanical member to repeat signals received by said tube.

60 4. In a telegraph system, an electron discharge device responsive to a received electrical

signal impulse, a plate circuit for said discharge device, a relay, a winding for said relay and a pair of normally closed contacts included in said plate circuit, a signal repeater, and a mechanical device operated by said relay whereby said mechanical device is operable to condition said repeater and to engage and open said normally closed contacts in response to the operation of said relay.

5. In a telegraph repeating device, a gas filled tube having a grid under the control of received signal impulses to start ionization of the tube, a mechanical work element electromagnetically associated with said tube for operation by said tube, means mechanically controlled by said work element for de-ionizing the tube simultaneously with the operation of said work element, and signal repeating means operated in accordance with the effectiveness of said tube under the control of said mechanical work element to repeat signals received by said tube.

6. In a telegraph repeating device, a gas filled tube having a grid under the control of received signal impulses to start the plate current of the tube, a mechanical work element electromagnetically associated with the plate circuit of said tube, electrical contacts included in the plate circuit of said tube operated mechanically by said work element to stop the plate current of the tube, and signal repeating means operated in accordance with the effectiveness of said tube under the control of said mechanical work element to repeat signals received by said tube.

7. In a telegraph signal receiving system, a gas filled tube, a telegraph transmitter connected to the grid of said tube through a signaling conductor and effective to initiate conductivity in said tube, an output receiving element normally closed contacts connected in series with the plate of said tube, mechanical means electromagnetically associated with said output receiving element for mechanically opening said contacts in the plate circuit of said tube, and signal repeating means operated in accordance with the effectiveness of said tube under the control of said mechanical means to retransmit regenerated electrical signals.

8. In a telegraphically controlled signal receiving device, a spring-urged circuit controlling member, electromagnetic means normally retaining said member in its unoperated position, means to operate said electromagnetic means to release said member for operation, a telegraphically controlled electron discharge device having a plate circuit including said electromagnetic means to operate said electromagnetic means in response to received signals, means controlled by said spring-urged member in its operated condition for interrupting current in said plate circuit, and signal repeating means operated in accordance with the effectiveness of said electron discharge device under the control of said spring urged member to transmit regenerated electrical signals.

9. In a telegraphically controlled signal receiving device, a gas filled tube, a magnet having a plurality of windings, a spring-urged armature for said magnet, a polarized circuit through one winding of said magnet with sufficient current to hold said armature against the urge of said spring in close-to-core position, a plate circuit for said tube through another winding of said magnet, means to polarize said tube by a received signal to permit current in said plate circuit to oppose said polarizing current

10 in said magnet and to release said armature, and means controlled by said armature to generate a repeating telegraphic signal and to open said plate circuit.

10. In a telegraph system, a pair of gas filled tubes, a first relay a winding of which is connected in the plate circuit of a first tube when the relay is unenergized, a second relay a winding of which is connected in the plate circuit of the second tube when the relay is unenergized, means to render the plate circuit of either tube conducting according to received signals and to energize the associated relay winding, means effective when the first relay is energized to open the plate circuit of the associated tube and close a locking circuit for the first relay through the contacts of the second relay, and means effective after the winding of the second relay is energized to interrupt the plate current of the second tube and to interrupt the holding circuit of the first relay.

11. In a telegraph system, a signal impulse generator, a signal repeating means, a space discharge device responsive to signal impulses emitted by said generator, a plate circuit for said space discharge device including an electromagnetic device, a plurality of mechanical members operated by said electromagnetic device, one of said members being operable to open said plate circuit and another of said members being operable to control said signal repeating means to repeat the signal impulse to which said space discharge device responds.

12. In a telegraph system, a signal generator, a pair of gas filled tubes one of which is rendered conductive by generated signals of marking nature and the other of which is rendered conductive by generated signals of spacing nature, an electromagnetic relay energized by one of said tubes and deenergized by the other, repeating mechanism controlled by said relay to repeat signals received by said tubes, and a mechanical member positioned by said relay simultaneously with the conditioning of said repeating mechanism to render said tubes inoperative.

13. A transmitting distributor comprising a plurality of signal transmitting segments, a closed conductive ring, a set of rotating brushes bridging said ring and said plurality of segments successively, a set of timing contacts, a transmission circuit including said set of contacts, said conductive ring, said plurality of segments and said set of brushes, means to operate said set of contacts to time transmission of initiatory impulses from said distributor segments, trigger tubes in said transmission circuit responsive to said initiatory impulses, an electromagnetic means controlled by said tubes, and signal repeating means operated in accordance with the effectiveness of said tubes under the control of said electromagnetic means to transmit regenerated electrical impulses.

14. In a telegraph system, a signal transmitter, a plurality of signal transmitting contacts in said transmitter operable in succession to generate impulses of a signal combination, a single set of timing contacts operated in synchronism with said transmitting contacts to determine the time of signal transmission therefrom, a pair of gas filled tubes, an electromagnetic relay individual to each tube and included in the plate circuit of their respective tubes, means to render the plate circuit of either tube conducting according to received signals and to energize the associated relay, means effective when one relay

is energized to open the plate circuit of the associated tube and close a locking circuit for said relay through the contacts of the other relay, and means effective after the winding of said other relay is energized to interrupt the plate circuit of the second tube and to interrupt the holding circuit of said one relay.

15. In a telegraph system, a signal generator, a pair of electron discharge devices each including a control electrode, each control electrode being individually connected to said generator whereby one of said discharge devices is rendered conductive by generated signals of marking nature and the other discharge device is rendered conductive by generated signals of spacing nature, a signal regenerator conditioned in response to the conductivity of said discharge devices to repeat signals received thereby, and means operable upon the conditioning of said signal regenerator to disable the discharge device that conditioned the signal regenerator.

16. In a telegraph system, a signal generator, a pair of electron discharge devices including control grids, the control grids of said discharge devices being individually connected to said signal generator whereby one of said devices is rendered conductive by generated signals of marking nature and the other is rendered conductive by generated signals of spacing nature, a signal repeater controlled by the conductivity of one of said discharge devices to repeat a marking signal and controlled by the conductivity of the other discharge device to repeat a spacing signal, and a single means to interrupt the conductivity of that discharge device that controlled the repeater.

17. In a telegraph system, a signal generator, a pair of electron discharge devices including control grids, the control grids of said discharge devices being individually connected to said signal generator to render one of said devices conductive by generated signals of marking nature

and to render the other discharge device conductive by generated signals of spacing nature, a signal responsive mechanism to be conditioned alternately by said discharge devices in response to received signals, and circuit means associated with said discharge devices operable upon the conditioning of said signal responsive mechanism to disable the discharge device that conditioned the signal responsive mechanism.

18. In a telegraph system, a signal generator, a pair of electron discharge devices each including a control grid, the control grid of each of said devices being individually connected to said signal generator to render one of said devices conductive in response to the generated signals of marking nature and to render the other discharge device conductive in response to generated signals of spacing nature, plate circuit for said discharge devices, a signal repeater to be conditioned selectively in response to current in said plate circuits, and means included in said repeater operable upon the conditioning of said repeater to interrupt the plate circuit of that discharge device that conditioned the signal repeater.

19. In a telegraph system, a signal impulse generator, a pair of electron discharge devices responsive to electrical signal impulses transmitted from said generator, a plate circuit individual to each device, a signal repeater including in said plate circuits to repeat signal in response to the operation of said discharge devices, means to cause said repeater to generate a lengthened signal impulse in response to a shorter signal generated by said generator, and mechanism included in said repeater operable upon the conditioning of said repeater in response to certain received signals to disable said plate circuit of that discharge device that conditioned the signal repeater.

LOUIS M. POTTS.
